UNITED STATES PATENT OFFICE

JOHN B. WESTOVER, OF HOUSTON, TEXAS

DESIGN FOR A CLOCK CASE

Application filed June 12, 1931. Serial No. 40,169. Term of patent 14 years.

To all whom it may concern:

Be it known that, I, JOHN B. WESTOVER, a citizen of the United States, residing in Houston, county of Harris, and State of Texas, have invented a new, original and ornamental Design for Clock Cases, of which the following is a specification, reference being had to the accompanying drawings, forming a part thereof, wherein—

Figure 1 shows a front elevation of the clock case showing my new design, and
Figure 2 shows a side elevation thereof.

I claim:
The ornamental design for a clock case as shown.

JOHN B. WESTOVER.
